UNITED STATES PATENT OFFICE.

BLYE SCOTT, OF MEMPHIS, TENNESSEE.

TRUCK.

No. 905,938.

Specification of Letters Patent.

Patented Dec. 8, 1908.

Application filed February 27, 1908. Serial No. 418,151.

To all whom it may concern:

Be it known that I, BLYE SCOTT, citizen of the United States, residing at Memphis, in the county of Shelby and State of Tennessee, have invented certain new and useful Improvements in Trucks, of which the following is a specification.

This invention comprehends certain new and useful improvements in trucks for railway cars and the primary object of the invention is to provide a truck of this type in which both the side frames and the bolster and their related parts will be of simple, durable and light construction capable of being cheaply manufactured and readily assembled.

With these and other objects in view as will more fully appear as the description proceeds, the invention consists in certain constructions, arrangements and combinations of the parts that I shall hereinafter fully describe and then point out the novel features in the appended claims.

For a full understanding of the invention, reference is to be had to the following description and accompanying drawings, in which:

Figure 1 is a perspective view of a bolster constructed in accordance with my invention; Fig. 2 is a longitudinal sectional view thereof; Fig. 3 is a transverse sectional view; Figs. 4 and 5 are fragmentary perspective views of parts of a bolster; Fig. 6 is a perspective view illustrating the bolster in its operative relation to the side frames of the truck; Fig. 7 is a detail view illustrating the parts of one of the side frames shown detached from each other; and, Fig. 8 is a detail side elevation illustrating a modification hereinafter specifically referred to.

Corresponding and like parts are referred to in the following description and indicated in all the views of the drawings by the same reference characters.

The bolster 1 of my improved railway truck is preferably composed of four main parts, which embodies two side pieces 2 of steel with angularly disposed ends 3, and two intermediate pieces or web portions 4 with angularly disposed ends 5 set back from the extremities so as to define flanges 6. In assembling these parts, the two longitudinally extending webs 4 are set back to back with their angularly disposed ends 5 facing outwardly in opposite directions, as shown and the two side pieces 2 are then placed

with their ends 3 facing each other and extending over ends 5, the extremities of the ends 3 abutting against the flanges 6 so as to form a strong and light box-like structure 60 with a double longitudinal web.

Fitted within the space between the side pieces 2 and the webs 4 are two truss supporting struts 7. Each of these embodies a substantially flat plate on the upper side 65 of which are two I-shaped tenons 8 spaced from each other as shown. The two ends of each tenon fit in the spaces between the webs 4 and side pieces 2 and are securely bolted thereto, the space between the two 70 I-shaped tenons accommodating the double web, as clearly illustrated in the drawing. On the opposite side of the plate of each truss strut 7 are two depending flanges 9, the lower ends of which are recessed as indicated at 10 so as to receive the truss rods 11. These rods are connected together at their inner ends by a turn-buckle or sleeve 12 and the outer ends of the truss rods pass through bolt holes formed for them in the 80 overlapped ends of the side pieces 2 and webs 4, the nuts on the outer ends of the bolts thereby serving the double function of securing the truss rods in place and holding the outer sections of the bolster together. 85

13 designates the center plate which fits upon the upper side of the bolster 1 between the two truss supporting struts 7, the said center plate being also formed with spaced I-shaped tenons 14 fitting in and securely 90 bolted to the side pieces and webs of the bolster. Each of the webs 4 is preferably formed with a crimped portion at its middle, the inner face of the crimp forming a recess facing a corresponding recess in the 95 other web, so as to provide a substantially circular opening 15 extending through the middle of the bolster.

17 designates the saddles for the truss rods 11, said saddles projecting inwardly from 100 the side pieces 2 and preferably formed integral therewith, as indicated in Fig. 2.

In connection with the bolster constructed as above described, the improved truck of my invention embodies two side frames, 105 illustrated in Figs. 6 and 7. Each side frame embodies an upper arch bar 18, a lower arch bar 19, which latter is formed with a seat 20 for the bolster supporting springs, and a pair of column posts 21 interposed between the upper and lower arch bars 18 and 19. Each column post 21 is ar-

ranged to work within the flanges of a column post guide 22 bolted, riveted, or otherwise secured to the bolster at the ends of the outer side pieces 2, as clearly illustrated in Figs. 1 and 6. Each of the pieces forming the column post 21 is of substantially T-shape, as best seen in Fig. 7 and embodies a substantially horizontal member 23 on the outer end of which is formed a vertical member 24. This latter is adapted to abut against the inner side of the sectional journal box post 25, the two sections of which are formed as upwardly and downwardly projecting thickened portions of the ends of the arch bars. The part 24, in the embodiment of the invention illustrated in Figs. 6 and 7 also serves as a section of the journal box post and as a means for securing together the outer ends of the arch bars. The column post 21 in this form of the invention is formed with upper and lower tenons 26 fitting within mortises 27 in the respective arch bars and secured therein by key bolts 28 as shown.

29 designates the bolster supporting springs seated on the plate or seat 20 of the lower arch bar.

As another form of my invention, reference is to be had to Fig. 8, in which 18^a designates the upper arch bar, 19^a the lower arch bar, and 21^a the column post. In this form of the invention, the column post 21^a with its horizontal member 23^a and vertical member 24^a, are formed as integral parts of the lower arch bar 19^a, and the vertical member 24^a is recessed as indicated at 30, so as to form a scarf joint with the depending projection 25^a so as to form a journal box post, bolts 31 passing through the parts, 40 as indicated in Fig. 8 so as to secure the upper and lower arch bars together in a firm manner. In this modification, also, the column post 21^a is formed with a tenon fitting in a mortise in the upper arch bar and 45 a key bolt 28^a extends therethrough to lock the parts.

From the foregoing description in connection with the accompanying drawings, it will be seen that I have provided a very simple, strong and efficient construction of car truck including a novel construction and arrangement of the parts, the parts being capable of being cheaply manufactured and easily assembled and when assembled producing a durable structure.

Having thus described the invention, what is claimed as new is:

1. In a car truck of the character de-

scribed, a bolster comprising side pieces formed with inwardly turned ends, web 60 pieces interposed between said side pieces and formed with outwardly projecting ends set back from their extremities and defining flanges against which the inwardly turned ends of the side pieces are adapted to abut, 65 the web pieces being disposed back to back, and means for securing the side pieces and webs together.

2. In a car truck of the character described, a bolster comprising a pair of webs 70 provided with outwardly projecting ends, a pair of side pieces formed with inwardly turned ends overlapping the outwardly projecting ends of the webs, and truss rods extending at their ends through the overlapped ends of the webs and side pieces.

3. In a car truck of the character described, a bolster comprising a pair of webs provided with outwardly projecting ends, 80 a pair of side pieces formed with inwardly turned ends overlapping the outwardly projecting ends of the webs, and truss rods extending at their ends through the overlapped ends of the webs and side pieces, the side pieces being formed with saddles upon 85 which said truss rods rest, and struts secured to and depending from the side pieces and webs, the truss rods extending across and being engaged with said struts.

4. In a truck of the character described, a 90 bolster embodying a web and side pieces spaced therefrom in the direction of the length of the bolster, the webs and side pieces being formed with overlapping ends, truss rods extending through said ends, and 95 truss rod struts formed with I-shaped tenons projecting up between the web and side pieces, the truss rods extending across and engaging said struts.

5. In a truck of the character described, a 100 side frame for a bolster, said side frame comprising an upper arch bar, a lower arch bar, column posts interposed between the arch bars and secured thereto, each column post embodying a horizontally extending 105 member, and a vertical member at the outer end of said horizontal member, the arch members projecting beyond said vertical member.

In testimony whereof I affix my signature 110 in presence of two witnesses.

BLYE SCOTT. [L. s.]
